Design No. 18,321, dated May 15, 1888.

UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,321, dated May 15, 1888.

Application filed April 20, 1888. Serial No. 271,349. Term of patent 3½ years.

To all whom it may concern:

Be it known that I, JENNIE SHEILS, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a round walking-skirt and a basque. The skirt displays a flat drapery falling in deep kilt plaits in front and with a panel effect between and at either side of the plaits in each side, and exhibiting pointed straps crossing between the latter plaits in groups of three; a full front drapery graduating in depth from the right edge near the belt to the lower edge at the left side, and displaying draping plaits in its right side edge and in

the top and jabot folds at its front edge, the right edge disappearing under the fourth kilt plait from the center; a full back drapery falling in jabot folds at its center and in loose folds at either side. The basque displays a V-vest between close-fitting fronts, three pointed straps crossing diagonally above the bust; a close-fitting back falling in a flat postilion that is open at the center; coat sleeves, and a standing collar with a pointed overlapping end. 25 30

What I claim as my invention, and desire to secure by Letters Patent, is—

The design for a lady's costume, as shown in the engraved prints accompanying this specification.

JENNIE SHEILS.
